**SHUTTER FLASH SYNCHRONIZING APPARATUS
FOR PHOTOGRAPHIC EQUIPMENT OR SIMILAR
ARTICLE**

Ralph T. Gardner, Denver, Colo.

Application February 11, 1957, Serial No. 44,840

Term of patent 14 years

(Cl. D61—1)

Fig. 1

Fig. 3

Fig. 2

Fig. 4

Figure 1 is a front perspective view of a shutter flash synchronizing apparatus for photographic equipment or similar article, showing my new design in one position with the platform extension omitted for convenience in illustration;

Figure 2 is a rear perspective view thereof in another position;

Figure 3 is an exploded top plan view thereof in another position; and

Figure 4 is an exploded end elevational view thereof.

I claim:

The ornamental design for a shutter flash synchroniz-

ing apparatus for photographic equipment or similar article, as shown and described.
